US00D485849S

(12) **United States Design Patent**
Sanschagrin et al.

(10) Patent No.: **US D485,849 S**
(45) Date of Patent: ** Jan. 27, 2004

(54) **ELEMENTS OF A COWLING**

(75) Inventors: **Stephane Sanschagrin, St-Hyacinthe (CA); Pierre Vignau, Montreal (CA)**

(73) Assignee: **Bombardier Motor Corporation of America, Grant, FL (US)**

(**) Term: **14 Years**

(21) Appl. No.: **29/183,425**

(22) Filed: **Jun. 12, 2003**

Related U.S. Application Data

(62) Division of application No. 29/175,384, filed on Feb. 4, 2003, which is a continuation of application No. 29/159,706, filed on Apr. 26, 2002, now Pat. No. Des. 474,784.

(51) **LOC (7) Cl. 15-01**

(52) **U.S. Cl. D15/4**

(58) **Field of Search** D15/1-5; 440/3-6, 440/52, 88, 495; 123/495; 290/43-46, 54

CLAIM

The ornamental design for elements of a cowling, as shown and described.

DESCRIPTION

FIG. 1 is a rear perspective view of the left side element of elements of a cowling showing our new design;

FIG. 2 is a front perspective view of the left side element; FIG. 3 is a front elevational view of the right and left side elements;

FIG. 4 is a left side elevational view of the left side element, the right side view and element is a mirror image thereof; FIG. 5 is a rear perspective view of the left side element of elements of a cowling showing a second embodiment of our new design;

FIG. 6 is a front perspective view of the left side element of FIG. 5;

FIG. 7 is a left side elevational view of the left side element of FIG. 5, the right side view and element is a mirror image of FIG. 5;

FIG. 8 is a rear perspective view of the left side element of elements of a cowling showing a third embodiment of our new design;

FIG. 9 is a front perspective view of the left side element of FIG. 8; and,

FIG. 10 is a left side elevational view of the left side element of FIG. 8, the right side view and element is a mirror image of FIG. 8.

Where included, broken lines showing environment or structure are for illustrative purposes only and and form no part of the claimed design.

1 Claim, 10 Drawing Sheets
